CLAIM

The ornamental design for a multifunction mosquito repellent light, as shown and described.

DESCRIPTION

FIG. 1 is a top, front and right side perspective view of a multifunction mosquito repellent light showing my new design;

FIG. 2 is a bottom, rear and left side perspective view thereof;

FIG. 3 is a top, front and left side perspective view thereof;

FIG. 4 is a front elevational view thereof;

FIG. 5 is a rear elevational view thereof;

FIG. 6 is a left side view thereof;

(Continued)

FIG. 7 is a right side view thereof;
 FIG. 8 is a top plan view thereof; and,
 FIG. 9 is a bottom plan view thereof.

The broken lines in the drawings illustrate portions of the multifunction mosquito repellent light which form no part of the claimed design.
